UNITED STATES PATENT OFFICE.

RALPH D. KIRCHER, OF BEDFORD, OHIO, ASSIGNOR TO WILLIAM BUDDOCK, OF CLEVELAND, OHIO.

CLAM-SHELL BUCKET.

1,177,634.

Specification of Letters Patent. Patented Apr. 4, 1916.

Application filed June 14, 1915. Serial No. 34,081.

To all whom it may concern:

Be it known that I, RALPH D. KIRCHER, a citizen of the United States, resident of Bedford, county of Cuyahoga, and State of Ohio, have invented a new and useful Improvement in Clam-Shell Buckets, of which the following is a specification, the principle of the invention being herein explained and the best mode in which I have contemplated applying that principle, so as to distinguish it from other inventions.

My invention relates to clam-shell buckets, its object being to construct a bucket of the double-line type which will be economical of manufacture and efficient in its operation.

The said invention consists of means hereinafter fully described and particularly set forth in the claims.

20 The annexed drawings and the following description set forth in detail certain means embodying my invention, the disclosed means, however, constituting but one of various mechanical forms in which the principle of the invention may be applied.

In said annexed drawings:—Figure 1 represents a side elevation of a clam-shell bucket embodying my invention, showing the scoop-members in their closed position. 30 Fig. 2 represents a section taken upon the plane indicated by lines II—II in Fig. 1. Fig. 3 represents a side elevation of the bucket showing the scoop-members in their open position. Fig. 4 represents a front elevation of the bucket. Fig. 5 represents an enlarged detail section of one end of the bell-crank forming part of the device. Fig. 6 represents a side elevation of the parts shown in Fig. 5. Fig. 7 represents a detail section taken upon the plane indicated by line VII—VII in Fig. 1.

The illustrated embodiment of my invention comprises two scoop-members 1, 1, of any accepted construction, the inner portion 45 of each of which is provided with two fixed lateral arms 2, 2. The extreme inner ends of these arms are formed with bearings 3, 3, for the reception of a journal-rod 4.

Intermediately of these inner ends of these 50 arms and formed with a bearing 5 for the reception of the said rod 4, is a bell-crank 6, Figs. 1 and 4.

Upon the end of one of the arms of this crank is mounted a sheave 7 and the end of 55 the other arm is formed with a journal 8

in which is mounted a rotatable sleeve 9 having a cross-section presenting four equidistant lobes, as shown in Fig. 6. This cross-section is designed to receive the links of a collapsible member such as a chain 10 which passes therethrough, as shown in Fig. 2. This last described structure performs a function which will be hereinafter described.

An upper head 11 formed of two plates, 65 separated from and secured to each other by means of suitable separators, has passing therethrough a pin 12, the outer ends of which form journals for the upper ends of two sets of arms 13, 13. Mounted in opposite ends of this head are the sheaves 14 and 15 respectively. Secured to the upper portion of the head is a member 16 to which the end of the hoisting line 17 is suitably secured.

75 The closing line 18 passes downwardly around the inner portion of the periphery of the sheave 15, then around sheave 7 from whence it passes around sheave 14 and thence to a strap 19 which is oscillatorily 80 mounted upon the end of the arm of the bell-crank upon which the sheave 7 is mounted. The connection between the strap and this arm is conveniently made by passing the pin 20 which forms the journal 85 for the sheave 7, through eyes formed in the end of this strap, as will be readily understood.

A strap 21 is similarly mounted upon the pin 22 of the sheave 15, to which the two 90 ends of the chain 10 are suitably secured, this chain, as before described, passing through the sleeve 9 mounted upon the end of one arm of the bell-crank. This chain is made of a link such that it will 95 form a means for limiting the open position of the scoop-members, as shown in Fig. 3.

Assuming the bucket to be in the position shown in Fig. 1, when it is desired to open 100 same, the closing line 18 is slackened away which permits the inner ends of the scoop-members to drop and these members to open out. This slackening away is continued until the scoop-members assume their extreme 105 open position, as shown in Fig. 3, the bell-crank during this operation oscillating on its axis. During this movement the sleeve 9 will turn in its bearing permitting the chain to retain a fixed position with reference to 110

such sleeve and thus eliminating any frictional action between the chain and the arm directly. Before the scoop-members, however, assume their extreme open position, 5 the weight of such members will be applied to the chain and through it to the head 11. This head will therefore, at the end of the opening movement, be pulled downwardly and in so doing acts as a shock absorber, 10 preventing the too sudden stopping of the movements of the parts, as will be readily understood. Furthermore by providing the oscillatory bell-crank and connecting same with the closing line, as described, as well 15 as connecting it with the head by means of the chain, I am enabled to effect a substantially equal application of power to each of the buckets during the closing operation, causing each scoop-member to travel an 20 equal distance during such operation.

Having fully described my invention, what I claim and desire to secure by Letters Patent is:—

1. In a clam-shell bucket, the combination 25 of two scoop-members having their inner ends oscillatory upon a movable axis and their outer ends mounted upon a stationary axis; an arm having its axis coinciding with said movable axis and mounted so as to be 30 oscillatory with reference to said axis; an oscillatory head having its axis coinciding with said stationary axis; sheaves mounted upon said head and said arm; a closing line 35 passing around said sheaves; and a separate member connecting said head and arm.

2. In a clam-shell bucket, the combination 40 of two scoop-members having inwardly extending members mounted upon a common journal-rod; a head; arms oscillatorily mounted upon said head and articulating with the outer portions of said scoop-members; a bell-crank mounted upon said journal-rod; sheaves mounted upon said head; a sheave mounted upon one arm of said bell- 45 crank; a closing line passing around said sheaves; and means connecting the other arm of said bell-crank with said head.

3. In a clam-shell bucket, the combination 50 of two scoop-members having inwardly extending arms provided with bearings mounted upon a common journal-rod; a

head; arms having their upper ends articulating with said head and their lower ends articulating with the outer ends of said scoop-members a bell-crank oscillatorily 55 mounted upon said rod; sheaves mounted upon said head; a sheave mounted upon one arm of said bell-crank; a closing line passing around said sheaves and having one of its extremities secured to said arm; and a 60 chain connecting the other arm of said bell-crank with said head.

4. In a clam-shell bucket, the combination 65 of a head; a chain having its two ends secured to such head; and an oscillatory arm connected with the scoop-members; one end of said arm being provided with a bearing and a sleeve mounted therein, said sleeve being provided with a central axial opening through which said chain passes. 70

5. In a clam-shell bucket, the combination 75 of two scoop-members having their inner ends oscillatory upon a movable axis and their outer ends mounted upon a stationary axis; an arm having its axis coinciding with said movable axis and mounted so as to be oscillatory with reference to said axis; an oscillatory head having its axis coinciding with said stationary axis; sheaves mounted upon said head and said arm; a closing 80 line passing around said sheaves; and a separate and collapsible member connecting said head and arm.

6. In a clam-shell bucket, the combination 85 of two scoop-members having inwardly extending members mounted upon a common journal-rod; a head; arms oscillatorily mounted upon said head and articulating with the outer portions of said scoop-members; a bell-crank mounted upon said journal-rod; sheaves mounted upon said head; a sheave mounted upon one arm of said bell-crank; a closing line passing around 90 said sheaves; and collapsible means connecting the other arm of said bell-crank with said head. 95

Signed by me, this 11th day of June, 1915.

RALPH D. KIRCHER.
